UNITED STATES PATENT OFFICE.

BLAINE EWING, OF NEW YORK, N. Y.

DESIGN FOR A CUSPIDOR.

48,713.

Specification for Design.

Patented Mar. 14, 1916.

Application filed January 22, 1915. Serial No. 3,846. Term of patent 3½ years.

To all whom it may concern:

Be it known that I, BLAINE EWING, a citizen of the United States, and resident of the borough of Manhattan, city, county, and State of New York, have invented a new, ornamental, and original Design for a Cuspidor, of which the following is a specification, reference being had to the accompanying drawing, forming part thereof.

Figure 1 is a perspective view of a cuspidor showing my new design; and Fig. 2 is an end view thereof.

Copies of this patent may be obtained for five cents each, by addressing the "Commissioner of Patents, Washington, D. C."

I claim:

The ornamental design for a cuspidor, as shown.

In testimony whereof I have signed this specification in the presence of two subscribing witnesses.

BLAINE EWING.
